William S. Rock, Inventor.

By his Attorney.

Phil. T. South.

UNITED STATES PATENT OFFICE.

WILLIAM S. ROCK, OF DAYTON, OHIO, ASSIGNOR OF ONE-HALF TO WILLIAM W. KIRKPATRICK, OF SAME PLACE.

PARCEL-CLASP.

SPECIFICATION forming part of Letters Patent No. 387,737, dated August 14, 1888.

Application filed February 24, 1888. Serial No. 265,210. (No model.)

To all whom it may concern:

Be it known that I, WILLIAM S. ROCK, a citizen of the United States, residing at Dayton, in the county of Montgomery and State 5 of Ohio, have invented a new and useful Parcel Clasp or Device for Grocers, &c., of which the following is a specification.

The object of my invention is to provide a handy device for grocers and others to be used 10 in lifting parcels—such as canned goods, lamp-chimneys, &c.—which are placed upon shelves out of reach without climbing upon something to reach them.

My device is a circle clasp; and it consists 15 of the peculiar construction and combination of the parts hereinafter fully described, and pointed out in the claim.

The figure in the accompanying drawing illustrates a view in perspective of my invention.

Referring to the drawing, the letter A represents a handle. B and C are jaws with extensions b b'. N is a spiral spring. D is a thimble or socket. L is a string or wire. f 25 and g are screws. h is an opening; j and k, guides; d', rough surface on face of jaws; and n u' are rings.

In the construction of my clamp, which is made of metal, I use an ordinary wood handle, 30 A, to the upper end of which the lower stationary jaw, B, is secured by means of a socket, D, formed integral with the jaw, and a screw, f, passing through the socket into the handle, as shown. To one side of the extension b is a 35 guide, j, through which is passed the operating string or wire L.

The letter C represents the top or movable jaw, which is pivoted upon the lower stationary jaw, B, by means of a screw, g, passing 40 through a hole in both of the jaws and into the upper end of handle A. This screw acts

as a pivot upon which the upper movable jaw turns. The jaws are made in circular form and the inner surfaces thereof are roughened or corrugated, as shown at d'. In practice I 45 use an ordinary spiral spring, which is secured to the side of the jaw C at n and to the extension b of jaw B at u'. This spring is for the purpose of releasing the jaws when they have been closed around the article when said article has been placed where it is desired. Near 50 the end of the extension b' of the jaw C is a hole, h, through which the string is passed, and is made fast at that point and is carried over to the extension b of jaw B. Thence it 55 passes through a guide, j, on extension b, and then downward toward the upper end of the handle A, where it is inserted through a guide, k, on said handle.

The operation of my invention is as follows: 60 The end of the stationary jaw B is placed on one side of the article. The jaw C is then arranged around the other side of the article, and by pulling the string the said jaws will 65 embrace the article, holding it fast until lifted out of its place and deposited where desired.

Having described my invention, what I claim is—

The combination, with the handle A, the stationary jaw B, having the extension b and 70 socket D, formed with said jaw, and said socket connected to the top of handle A, of the pivoted jaw C, having extension b', the spring N, connecting said movable jaw and extension of the stationary jaw, and the wire 75 or string connected to extensions b b' and handle A, as shown and described.

WILLIAM S. ROCK.

Attest:

J. P. Rock,
THOS. L. ROCK.
